CLAIM

The ornamental design for a dental explorer tool, as shown and described.

DESCRIPTION

FIG. 1 is a side view of a dental explorer tool;
FIG. 2 is a side view of a dental explorer tool rotated ninety degrees from FIG. 1; and,

FIG. 3 is a top view of a dental explorer tool.

Any shading and cross-hatching are not features of the design but are utilized to illustrate surface contours of the dental explorer tool in the drawings.
